(57) **CLAIM**

The ornamental design for a boot for connector, as shown and described.

DESCRIPTION

FIG. 1 is a front elevational view of a boot for connector showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom plan view thereof;

FIG. 7 is a perspective view showing a front, top and right side thereof;

FIG. 8 is a perspective view showing a rear, bottom and left side thereof;

FIG. 9 is a perspective view showing a front, right side and bottom thereof;

FIG. 10 is a perspective view showing a rear, left side and top thereof; and,

FIG. 11 is a sectional view thereof taken along line 11-11 in FIG. 1.

The broken lines shown represent portions of the boot for connector that form no part of the claimed design.

1 Claim, 7 Drawing Sheets
